UNITED STATES PATENT OFFICE.

ALBERT A. D. SHEPARD, OF SEATTLE, WASHINGTON.

OIL-BURNER.

1,181,413.

Specification of Letters Patent.

Patented May 2, 1916.

Application filed July 3, 1915. Serial No. 37,806.

To all whom it may concern:

Be it known that I, ALBERT A. D. SHEPARD, a citizen of the United States, and a resident of Seattle, in the county of King 5 and State of Washington, have invented certain new and useful Improvements in Oil-Burners, of which the following is a full, true, and exact specification.

My invention relates to oil burners for use 10 with boilers, stoves or the like, and has for its principal object to provide an improved and novel device in which water is converted into steam and as such is discharged in close proximity with heated oil against a mixing 15 and deflecting pan from which the mixture of oil and steam is deflected to the burning flame.

A further object is to provide adjustable 20 means for regulating the quantity of oil and steam.

Still another object is to provide means for adjusting the deflecting pans so that the mixture may be thrown off at any desired angle.

25 Other objects will appear as my invention is more fully explained in the following specification, illustrated in the accompanying drawings and pointed out in the appended claims.

30 In the drawings, Figure 1 is a part plan view of my device with parts broken away. Fig. 2 is a cross sectional elevation of same.

Referring more particularly to the drawings, numeral 1 indicates a hollow body having 35 an oil chamber 2 and a water chamber 3 separated by a partition 4.

5 and 6 are water and oil inlet connections respectively and connect from sources not shown to chambers 3 and 2 respectively.

40 Ranged on either side of body 1 in horizontal lines, are oil lugs 7 and water lugs 8, one of each forming a pair which are in vertical alinement. Each lug is tapped for a valve plug 9 or 10 respectively. The 45 plugs 9 and 10 are counter-bored from the inner end and from the side a passage connects with the said counter-bored passage. Connecting holes are also bored through lugs 7 and 8 and at such angles that their

50 center lines produced will strike a deflecting pan 11 so that the stream of steam is but slightly behind the oil stream. Pans 11 are concaved on their upper face and are adjustably mounted on body 1 by ball and 55 socket joints 12 and screws 13.

It will be understood that the burner is suspended within the firebox of the stove or boiler and that the oil and water are supplied under pressure. The amount of oil and water calculated to make a correct mixture is regulated by setting plugs 9 and 10 so that the openings in the said plugs and the lugs 7 and 8 respectively either wholly register or only partially so. The oil and water may be shut off by simply turning the 60 plugs until the holes are out of register. A pair of plugs and a pan constitute a unit of which there may be any desired number ranged along the body 1 and each of which acts independently of the others. The heat 65 from the oil fire is sufficient to change the water into steam which disintegrates the oil as they are deflected from the pans 11 to the point of ignition. The pans 11 may be adjusted so that the mixture of oil and steam 70 may be deflected in any desired direction so that several units may be arranged to have the same point of ignition or they may be arranged to have varying points of ignition 75 as desired.

80 What I claim as new and desire to protect by Letters Patent, is:

1. In an oil burner, the combination of a 85 combined oil and water casing, having oil and water compartments being separated by a partition, pairs of adjustable valves one in each compartment adapted to discharge converging streams of oil and steam, deflecting pans one for each pair of valves, and means for adjusting the position of said 90 pans whereby the converging streams of oil and steam are inter-mixed and deflected at any desired angle to an ignition point.

2. In a device of the character described, 95 the combination of an oil compartment, a water compartment in which water is converted into steam, pairs of plug valves adapted to throw converging streams of oil and steam, one communicating with each compartment, and adjustable concave deflection pans one for each pair of valves, whereby the converging streams of oil and steam are intermixed and deflected to an ignition point.

3. In a device of the character described, 105 including a body having separate oil and water compartments therein and adapted to be suspended within the combustion chamber of a furnace, the combination of pairs of plug valves one communicating with each of 110

the said oil and water compartments and arranged to throw converging streams of oil and steam, said valves including cored screw plugs screwed into lugs on said body and having outlet holes which normally register with converging holes in said lugs, concave deflecting pans, one for each pair of

valves positioned within the path of the converging streams of oil and steam, ball and socket adjustable means for varying the position of said pans whereby the oil and steam are intermixed and deflected at any desired angle.

ALBERT A. D. SHEPARD.
